CHARLES E. UNDERWOOD AND JAMES A. BEATTY, OF BETHLEHEM, PENNSYLVANIA,
ASSIGNORS TO BETHLEHEM STEEL COMPANY

COKE-OVEN HEATING FLUE

Application filed April 27, 1926. Serial No. 104,894.

Our invention relates to an improvement in the means normally used to bridge the ends of the heating-flue walls of a by-product coke oven, and is more particularly directed to the 5 flash plates which cover the ends of the heating-flue walls and are held in position by the vertical buckstays of the oven. Hitherto it has been found difficult to maintain proper joints between the masonry of the flue walls 10 and the flash plates bridging them, due to their different coefficients of expansion.

Furthermore, the use of discharge rammers and the opening and closing of the oven doors contribute to the loosening of the joints 15 between the flash plates and the masonry walls, the constant repair of which adds materially to the operating expenses of the oven.

An object of this invention is, therefore, to design a flash plate of improved design, 20 to insure a substantially gas tight joint in the end masonry of the heating flues.

A further object of this invention is to provide a masonry construction at the end of the heating flues, wherein the normal joints 25 are suitably masked for the purpose of preventing gas leakage therefrom.

A further object of this invention is to protect the masonry at the ends of the flue side walls from abrasion by the discharge 30 rammer:

In the drawings:

Fig. 1 is a vertical elevation of a portion of a coke oven battery;

Fig. 2 is a transverse section along line 35 II—II of Fig. 1 of the coking chamber and its adjacent heating flues;

Fig. 3 is the upper portion of two adjacent coking chambers shown in elevation; and,

Fig. 4 is a part section along the line 40 IV—IV of Fig. 1.

In these figures we show a coking chamber 11, heating flue walls 12, defining the flues or combustion chambers 13 on each side of said 45 coking chamber. We also show the filler bricks 14, terminal portions 20 of the side walls, center bricks 25 and vertically superposed flash plate sections 15.

Referring to Fig. 2 it will be seen that the 50 flash plates 15 include inwardly projecting

flanges 16, external shoulders 17, buckstay recesses 18, and internal shoulders 19. The terminal bricks 20 are provided with recesses 21 to cooperate with the internal shoulders 19 of the flash plates, and are also recessed to engage the aforesaid inwardly projecting flanges 16 of said flash plates. Tongue and groove vertical joints are provided between the terminal bricks 20 and the center bricks 25. These joints are broken in alternate courses in the usual manner.

The position of the filler bricks 14 outwardly of the vertical joints is such as to oppose any leakage of gases from the heating flues therethrough. The flash plates embrace the filler brick and the terminal bricks of the side walls, being maintained securely against the terminal bricks by the engagement of the usual vertical buckstays in the recesses 18 provided in the flash plates. (For the sake of clearness said buckstays have not been shown on the drawing.) Furthermore, the inwardly projecting flanges 16 of the flash plates serve to protect the edges of the side walls from abrasion and fracture by the coke oven rammer and are flashed into suitable recesses in the terminal bricks 20. The external shoulders 17 of the flash plates also serve to form a seat for the oven doors.

From the above, it is evident that leakage 50 of gases from the heating flues is effectively opposed. In the event of gas leaking through the tongue and groove joints between the center and terminal bricks, it is prevented from further escape by the filler bricks 14, and in 55 the event that gas passes along the line of contact between the filler brick 14 and the terminal bricks 20, it would be finally checked by reason of the flash plate 15 which embraces the filler brick and the terminal end 60 bricks.

While we have shown our invention in but one form, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

Having thus described our invention what we claim as new and desire to secure by Letters Patent is:

1. In a coke oven heating flue, side walls and end bricks therebetween, the outer faces of the center bricks being substantially flush with the ends of the side walls, filler bricks disposed outwardly of the center bricks and masking the joints between the side walls and center bricks, and flash plates embracing the filler bricks and the terminal portions of the side walls.
2. In a coke oven heating flue, side walls and end bricks therebetween, the outer faces of the center bricks being substantially flush with the ends of the side walls, filler bricks disposed outwardly of the center bricks overlapping the joints between the side walls and center bricks, and flash plates embracing the filler bricks, having inwardly projecting flanges overlapping the line of contact between the terminal portions of the side walls and the filler bricks, the terminal portions of the side walls being recessed to receive the overlapping portions of the flanges.
3. In a coke oven heating flue, side walls and end bricks therebetween, the outer faces of the center bricks being substantially flush with the ends of the side walls, filler bricks disposed outwardly of the center bricks overlapping the joints between the side walls and center bricks, and flash plates embracing the filler bricks, having inwardly projecting flanges overlapping the line of contact between the terminal portions of the side walls and the filler bricks, the terminal portions of the side walls being recessed to receive the overlapping portions of the flanges, the flanges being shaped to provide a seat for an oven closure.
4. In a coke oven heating flue, side walls, center bricks whose side faces engage the inner faces of the ends of the side walls, filler bricks engaging the ends of the side walls and the outer faces of the center bricks, and masking the joints between the side walls and center bricks, and flash plates embracing the filler bricks and the terminal portions of the side walls.
5. In testimony whereof I hereunto affix my signature this 22nd day of April, 1926.

CHARLES E. UNDERWOOD.

In testimony whereof I hereunto affix my signature this 22nd day of April, 1926.

55 JAMES A. BEATTY.

CERTIFICATE OF CORRECTION.

Patent No. 1,751,775.

Granted March 25, 1930, to

CHARLES E. UNDERWOOD ET AL.

It is hereby certified that error appears in the printed specification of the above numbered patent requiring correction as follows: Page 2, lines 5, 14, and 27, claims 1, 2 and 3 respectively, for the word "end" read "center"; and that the said Letters Patent should be read with these corrections therein that the same may conform to the record of the case in the Patent Office.

Signed and sealed this 22nd day of April, A. D. 1930.
